194,251

BOAT BAILING PUMP OR SIMILAR ARTICLE

William M. Olds and Kenneth C. Browne, Jr., Columbus, and Charles D. Browne, Galena, Ohio, assignors to Browne Bros. Equipment Co., Columbus, Ohio, a corporation of Ohio

Filed Feb. 13, 1962, Ser. No. 68,804

Term of patent 14 years

(Cl. D65—1)

FIGURE 1 is a perspective view of a boat bailing pump or similar article showing our new design; and

We claim:

The ornamental design for a boat bailing pump or similar article, substantially as shown.
